CLAIM

We claim the ornamental design for a power module having pin fins, as shown and described.

DESCRIPTION

FIG. 1 is a front right side perspective view of a power module having pin fins;
FIG. 2 is a bottom right side perspective view of the power module having pin fins shown in FIG. 1;
FIG. 3 is a top view of the power module having pin fins shown in FIG. 1;
FIG. 4 is a left side view of the power module having pin fins shown in FIG. 1;
FIG. 5 is a right side view of the power module having pin fins shown in FIG. 1;
FIG. 6 is a bottom view of the power module having pin fins shown in FIG. 1;
FIG. 7 is a back side view of the power module having pin fins shown in FIG. 1; and,
FIG. 8 is a front side view of the power module having pin fins shown in FIG. 1.
In the drawings, the claimed design is defined by the shaded surfaces; broken lines immediately adjacent shaded surfaces represent boundaries of the claim and form no part thereof; all other broken lines depict unclaimed environmental subject matter and form no part of the claim.
